NUMBER PLATE

Albert W. Becker, Hartford, Conn., assignor of forty one-hundredths to Anthony Mauro, New Britain, Conn., and one-fourth to Adolph G. Bergmann and James H. Dunn, both of Ansonia, Conn.

Application October 12, 1937, Serial No. 168,600

4 Claims. (Cl. 40—125)

This invention relates to number plates and more particularly to such plates as are used for indicating the registration number of automobiles.

5 An object of this invention, is to provide a registration plate which may be used for a number of years, instead of a single year, and thereby greatly reduce the cost of supplying, as well as the expense for mailing large numbers of said 10 plates, which have heretofore amounted to many thousands of dollars annually for each State when motor vehicle registrations are renewed each year.

15 A further object of this invention is to provide a number plate having a separate plate which bears a number indicating the year of the registration, the said separate plate being so constructed that it may be changed by the registrant upon renewal of the registration.

20 Further objects and advantages of my invention will be clearly understood from the following description and from the drawing in which:

25 Figure 1 is a front view of a plate comprising my invention.

Figure 2 is a view in central vertical section on line 2—2 of Figure 1.

30 Figure 3 is a fragmentary view showing the panel on which the changeable year number plate is mounted.

Figure 4 is a rear view of the same illustrating the manner in which the said year number plate is attached thereto.

35 Figure 5 is an enlarged plan view in horizontal section through the year number plate on line 3—3 of Figure 1.

Figure 6 is a similar view through the year number plate panel with the said plate removed therefrom.

40 As illustrated in the drawing the numeral 5 denotes the registration plate embodying my invention which is preferably made of a durable sheet metal. The said plate has raised letters 6 indicating the serial, number and the State in which the said registration is made and raised figures 7 indicating the number of said registration.

45 My invention provides a raised panel 8 upon which is mounted an auxiliary number plate 9 having perforations 10 therethrough in the form of a year number. The said year number plate is attachable to the plate 5 by means of prongs 11 which are protruded through slots 12 in the said panel 8; the said prongs being bent downwardly upon the back surface of the license plate,

as indicated in Figure 4, to secure the year plate upon the said panel.

It will be noted from the illustration in Figures 5 and 6, that the letters 6 are raised upon the plate 5 in order that the indicia thereon may 5 clearly stand out.

It is to be understood that when a registration is renewed, the registrant is given a new year number plate 9 designating the new year. He is then required to remove the old plate and 10 attach the new one by protruding the prongs 11, as designated in dotted lines in Figure 5, through the slots 12 and bending them down against the back surface of the license plate. In bending the said prongs it is necessary to hammer them 15 down in order to securely attach the year number plate to the said license plate.

In order to eliminate possible damage to the other letters and figures 6 and 7 on the said license plate, I have provided the raised panel 20 8 upon the said license plate which is substantially on a level with the said letters and figures. The said panel is also provided with a depression 13 for receiving the year number plate.

The said depression is of a depth less than the 25 thickness of the year number plate so that the upper surface of the said plate will project above the surfaces of the other letters on the registration plate. Thus, when it is to be attached to the said registration plate, the year number plate 30 30 may be placed upon a surface, indicated by line 14 in Figure 5, with the prongs 11 thereof protruding through the slots 12. When in this position, it will be noted the surface of the other letters on the registration plate are spaced, by 35 the year number plate, above the said surface 14 so that the prongs 11 may be hammered down against the back of the registration plate without damaging the surfaces of the other letters.

In order to prevent theft of the year number 40 plate 9, for re-use thereof upon another registration plate, the said year number plate is constructed of a material having a degree of brittleness which will cause the prongs 11 to break off, upon attempt to rebend them for the purpose of detaching the year number plate, and thus render the said plate useless.

By stenciling the number through the year number plate, as indicated at 10, I have provided a number on said plate which is indestructible 50 and which will, at the same time, clearly show in the same color as the other letters on the registration plate. To accomplish this purpose, it will be clearly seen that, as illustrated in Figure 3 of the drawing, the surface of the panel 8 is 55

5 painted in the same color as the other insignia on the said registration plate so that when the year number plate 9 is attached thereto, the said color will provide a background which shows through the perforations forming the number indicating the year on said plate. The year number plate itself may also be made in different colors to additionally indicate the year of its issuance by means of the contrast between the 10 color of said plate and that of the background provided by the panel upon which the said year number plate is mounted.

15 The auxiliary plate 9 is smaller than the panel 8 so that when the said auxiliary plate is attached to the panel, a portion of the surface of said panel adjacent the edges thereof, will provide a border surrounding the auxiliary plate.

20 While I have illustrated and described one method of attaching a plate indicating the year to a registration plate, it is to be understood that the same may be attached by various other means without departing from the scope of my invention.

I claim:

25 1. The combination of a main plate having insignia thereon comprising letters and figures designating the serial, number and State of a registration and a panel thereon; the said letters, numbers and panel having raised surfaces on a substantially equal plane above said main plate, a color medium applied to said raised surfaces, a year number plate having perforations in the form of a number indicating the year of said registration mounted upon said panel and means 30

comprising prongs on said year number plate extending through openings on said panel and bent back upon the rear surface of said main plate for securing said year number plate thereon; the said year number plate being made of a material which is substantially brittle to cause 5 said prongs to break off of said year number plate upon bending thereof to remove the said year plate from the main plate.

2. A device of the character described comprising a main plate having indicia on its face, a raised panel having openings extending therethrough, an auxiliary plate comprising a stencil defining indicia thereon and prongs on said auxiliary plate adapted to extend through said openings for securing the same on said panel. 15

3. A device of the character described comprising a main plate having indicia and a raised panel on its face, the said panel having openings therein, an auxiliary plate having indicia thereon, and means adapted to extend through said openings for securing the said auxiliary plate upon said panel; the said auxiliary plate being smaller than the surface of said panel whereby the said 20 surface will provide a border surrounding said auxiliary plate. 25

4. In combination with a main plate having indicia and a slotted raised panel thereon, an auxiliary plate having stencil openings in the form of indicia and prongs extending through the 30 slots in said panel and bent against the back of said panel for securing said auxiliary plate thereon.

ALBERT W. BECKER.
